ABSTRACT OF THE DISCLOSURE

A T-shaped dielectric terminal block having three adjoining, partitioned, recessed portions formed axially on its outer side, the center portion being in the block leg and in parallel relation with the coextensive outer portions in the block head and housing a conductor strip in converting the block from a two terminal to a three terminal assembly with a self-locking fastener manually positioned through aligned openings in the strip and the block side for mounting the strip; the strip having a lip on one end lockingly engaging an undercut shoulder in the block and having an outstanding opposing end constituting a push-on connection and supporting a screw type connection intermediate its ends.

BACKGROUND OF THE INVENTION

While there are different types of terminal block assemblies used in various and differing electrical arrangements, most known terminal block units are made to be used with just one setup. Somewhat different manufacturing techniques must be employed for different production setups to tailor the terminal assemblies to the particular needs and requirements. For example, a two terminal block arrangement differs materially from a three terminal arrangement. Thus, if a customer originally specified a two terminal arrangement and then requires a three terminal one, considerable labor and material costs are involved in making the alteration or change.

For this reason, it is known in the art to utilize a terminal block whereby an initially determined and mounted circuit arrangement can be modified to meet most contingencies encountered during plant assembly. However, such terminal blocks and the associated terminal conductors or connectors are not easily modified and their very individual and cooperative structural natures necessitate that any changeover or modification be accomplished under plant assembly conditions at appreciable labor and material costs. It is necessary that factory trained labor, using tools of the trade, effect the changeover with materials similar to original production materials. Further, it is not possible, under usual conditions, that even skilled labor can make the conversion in the field.

In an effort to overcome the labor and material costs and to permit changeovers to be carried out in the field or place of use, it has been proposed, especially in the instance of conversions from two terminal to three terminal arrangements, to fabricate the terminal block originally with three terminals, the third terminal being incorporated in the block so that it can be selectively employed. In most instances, the third terminal is retractable in the block. However, the terminal assembly should, in its original design, be of a very simple, compact and relatively inexpensive nature for it is quite likely that the need or desire for conversion or addition will not occur. Therefore, in using such a concept, it can be appreciated that higher costs, which may not in operation be warranted, are involved.

SUMMARY OF THE INVENTION

In accordance with the present invention, compact and

2

inexpensive terminal block assembly of the add-on type is made initially to satisfy, in a highly efficient manner, the original working requirements and to be easily modified under field conditions by unskilled personnel without usage of tools and expensive materials so as to accommodate supplemental or additional circuit arrangements. While this objective is not restricted to two/three terminal block arrangements, it is particularly realized in the plant or field conversion of an initial two terminal assembly to a readily useable three terminal assembly. Also, instead of a cooperative third terminal in the terminal assembly, the modification can be effected simply for the reason of providing a convenience terminal for easily connecting two or more external wires which are not tied in with the specific utilization circuitry of the terminal block.

Another object of the present invention is to provide a terminal block which has a side or wall formed in a compact way for housing originally mounted terminal conductors and for accommodating, without sacrificing the original compactness or interfering with the initial terminal arrangement, one or more additional terminal conductors that are mounted thereon in a very simple and convenient but effective mounting fashion through the use of self-locking, manually insertable, fastener clips.

25 A further object of the present invention is to provide an add-on terminal in the form of a conductor bar or strip having an opening therein and to provide an aperture in the mounting side of the terminal block with which the opening is alignable for the common reception of a push-in fastener clip that is manually pushed through the strip opening into the block aperture and has a self-locking shank portion for anchoring engagement with the block and an enlarged end to captively overlie the strip, whereby a terminal conductor can be quickly and easily attached to the terminal block at any time by any unskilled personnel.

In practicing the present invention, a simple and compact terminal block structure is provided with an outer mounting wall or side for the accommodation of terminal conductors in the form of flat bars or strips, the side being formed with adjoining parallel recessed portions separated by barrier walls with each recessed portion serving as a housing for accommodating a terminal conductor strip; the block is especially designed in a planar T-shape having three recessed portions with the outer portions being in laterally spaced relationship in the head portion of the T-shaped block and housing the more or less permanent two terminal strips of a two terminal arrangement and with the center recessed portion being in the leg portion of the T-shaped block to accommodate the added-on third terminal strip, the central recessed portion being disposed in axially offset staggered and parallel relation with the outer portions.

These and ancillary objects, including the provision of an extremely simple, inexpensive and convenient but highly effective and durable terminal block assembly, are attained by this invention, the preferred embodiment of which is set forth in the following description and illustrated in the accompanying drawing, wherein:

BRIEF DESCRIPTION OF THE DRAWING

FIG. 1 is a perspective view of the terminal block assembly showing the housing arrangement for the terminal conductors with portions of the separating walls broken away to show more clearly the seating arrangement for the add-on terminal conductor, the housing arrangement in this illustrated instance, being for a two terminal arrangement that is convertible into a three terminal arrangement;

FIG. 2 is a fragmentary longitudinal vertical sectional view of the center recessed portion of the terminal block

showing the add-on third terminal conductor strip mounted on the block;

FIG. 3 is a perspective view of the add-on third terminal conductor strip, per se; and

FIG. 4 is a fragmentary transverse vertical sectional view taken substantially on line 4-4 of FIG. 2.

DESCRIPTION OF THE PREFERRED EMBODIMENT

Referring now more particularly to the accompanying drawing, the numeral 10 generally designates a dielectric terminal block which is of planar T-shaped, having a large transverse head portion 12 and a central longitudinally extending leg portion 14. The block 10 has an outer side or mounting wall 16 provided with three adjoining and parallel recessed portions 18, 20 and 22. The outer recessed portions 18 and 22 are formed axially of the block and are disposed in the head portion 12. Barrier walls 24 integrally upstand from the side 16 to define the recessed portions with the side and separate the outer recessed portions from the central recessed portion 20 which is in staggered, longitudinally offset relation with the coextensively extending outer recessed portions 18 and 22 and is disposed in the leg portion 14 of the block. A common end wall 26 upstands from the outer end of the head portion 12 and forms a back wall for the recessed portions, the barrier walls 24 and end wall 26 being in integral association and having coplanar outer edges in their integral outstanding relation with the block side 16.

The sections of the block side 16 within the outer recessed portions 18 and 22 provide mounting seats for the terminal conductor bars or strips 28 that are housed in the outer portions in an identical more or less permanent fashion and are of similar construction. Each terminal strip 28 supports a terminal screw 30 adjacent one end for the attachment of a lead connection to the terminal and has its opposing end portion 32 bent outwardly at right angles from the block side 16 and in inwardly spaced parallel relation with the end wall 26 to receive an external push-on type connector. A fastening pin 34 secures the terminal conductors 28 on the block side 16.

The terminal conductors 28 positioned in the outer recessed portions 18 and 22 constitute the terminal block as a two terminal block assembly that functions in any two terminal setup with the barrier walls 24 preventing arcing. In such setup, the center recessed portion is left void, as it appears in FIG. 1.

When it is desired to add a supplemental or convenience circuit to the terminal block, as in the instance of converting the terminal block assembly from a thusly provided two terminal assembly to a three terminal assembly, an add-on or third terminal conductor 36 is provided, as shown in FIG. 3, to be mounted in the central recessed portion 20, as shown in FIGS. 2 and 4.

The substantially flat rectangular conductor strip 36 has opposing faces, one of which is adapted to rest in the elongated seat 38 provided in the block side 16 within the central recessed portion 20. The seat 38 is formed at one end with a cavity 40 having an outer end wall 42, formed at its outer edge with an undercut shoulder 44, which constitutes a locking shoulder on the part of the block side 16 within the central recessed portion for interlocking engagement with the conductor strip 36. The opposite end of the seat 38 is vertically confronted in spaced fashion by the inwardly protruding center section 26a of the end wall 26.

The conductor strip 36 has an opening 46 formed therethrough and through its opposing faces with the opening being alignable with an aperture 48 provided in the part of the block side 16 within the central recessed portion. A fastener clip 50 is provided and has a resilient bifurcated shank portion 52 and an enlarged head 54. The legs of the bifurcated shank portion, which are pushed through

the aligned opening and aperture, are formed with laterally outstanding locking shoulders 56 that are adapted to anchor under the block side 16 adjacent the aperture 48 with the head 54 captively overlying the outer face of the conductor strip 36 to mount it in place.

The conductor strip 36 is formed at one end with an axially elongated locking lip 58 that projects longitudinally in a plane parallel to and below the plane of the positioned strip for positioning under and engagement with the shoulder 44, as shown in FIG. 2, to thereby assist the locking pin or clip 50 in anchoring the conductor 36 in place. The locking clip 50 is positioned adjacent the end of the conductor strip 36 opposite the lip end so as to cant the lip 58 in its interlocking engagement with the shoulder 44.

The conductor strip 36 is provided in the part thereof overlying the cavity 40 with a threaded opening 58 that passes through the opposing faces of the strip to receive a terminal screw 60, which is adapted to have an appropriate lead connector curled under the head thereof. The opposing end portion 62 of the conductor strip is bent outwardly at right angles to the conductor strip so as to standout normal to the outer face of the strip and has a tapered outer face end for the reception of an external push-on type connector. Thus, the mounted terminal conductor 36 can be used for a screw-type connection or as a push-on connection type terminal.

The terminal conductor 36 can be easily mounted in position by utilizing the fastener clip 50, as can be appreciated from a consideration of FIGS. 1 and 3, with the assemblage being effected by any untrained person without employing any tools. The converted arrangement is accomplished in a most facile manner by inserting the conductor strip 36 endwise in the recessed portion 20 until the lip 58 is caught under the shoulder 44 and the strip is laid flat on the seat 38 with the opening 46 and aperture 48 in alignment. The clip 50 is then manually held and pushed through the aligned opening and aperture into its locked relation with the block 10.

Inasmuch as the present invention is subject to many variations and changes in detail, it is intended that all matter contained in the foregoing description or shown on the accompanying drawing shall be interpreted as illustrative and not in a limiting sense.

What is claimed is:

1. A terminal block assembly comprising a dielectric terminal block having a well, said wall having an outer exposed mounting surface provided with spaced separate recessed portions, a terminal conductor strip adapted to be mounted in one of the recessed portions and fixedly positioned on the wall surface, said wall having an aperture formed therein within said recessed portion, said strip having opposing faces and having an opening formed therein and through the faces, said strip being superimposed on the wall surface with the opening aligned with the aperture in the wall, a fastener having a shank portion adapted to be pushed through the aperture and the opening, locking means carried by the shank portion for self-anchoring engagement with the wall, an enlarged end on the shank portion to overlie one face of the strip and hold the other face on the wall surface, electrical connection means carried by the conductor strip, said wall and said strip being provided with interlocking means conjunctively operative with the fastener to anchor the strip on the wall surface and said interlocking means including an undercut shoulder on the wall and an axially elongated offset lip on one end of the strip lockingly engageable under the shoulder.

2. The invention as recited in claim 1 wherein said wall surface is formed with integral normally outstanding partition walls, said partition walls being disposed in laterally spaced parallel relation and constituting barriers defining and separating the recessed portions, said recessed portions being in laterally spaced, parallel relation.

3. The invention as recited in claim 2 wherein a common end wall is provided for the recessed portions and is integral with the wall surface and projects perpendicularly therefrom at right angles to the partition walls and is integral with the partition walls at one of the ends thereof and is disposed transversely of the partition walls and the axis of the recessed portions to cooperate with the partition walls and the wall surface in defining the recessed portions.

4. The invention as recited in claim 1 wherein said electrical connection means includes an integral end portion on said conductor strip, said end portion being substantially perpendicularly offset from the plane of the anchored strip and having a tapered free end and constituting a 20 push-on connection.

5. A terminal block assembly comprising
a dielectric terminal block having a wall, said wall having an outer exposed mounting surface provided with spaced separate recessed portions,
a terminal conductor strip adapted to be mounted in one of the recessed portions and fixedly positioned on the wall surface,
said wall having an aperture formed therein within said recessed portion,
said strip having opposing faces and having an opening formed therein and through the faces, said strip being superimposed on the wall surface with the opening aligned with the aperture in the wall,
a fastener having a shank portion adapted to be pushed through the aperture and the opening,
locking means carried by the shank portion for self-anchoring engagement with the wall,
an enlarged end on the shank portion to overlie one face of the strip and hold the other face on the wall surface,
electrical connection means carried by the conductor strip,
said wall surface having a cavity in the recessed portion and underlying a part of the strip intermediate the ends thereof, means defining a threaded opening through the said part of the strip, a terminal screw adapted to be threaded into said opening for holding a connector lead curled under its head,
said fastener having its anchored shank portion disposed parallel to and on one side of the terminal screw along the longitudinal axis of the strip and said strip having an end portion disposed on the opposite side of the screw, said end portion terminating in an underlying axially elongated lip, said wall having an undercut shoulder lying below the plane in which the strip lies on the wall surface and formed at one end of the cavity, and said lip being positioned in the

cavity and lockingly engaging under the shoulder to cooperate with the fastener in anchoring the strip on the wall surface.

6. The invention as recited in claim 5 wherein said strip has an opposing end portion substantially perpendicularly offset from the plane of the positioned strip and having a free end and constituting a push-on connection.

7. A terminal block assembly comprising
a dielectric terminal block having a wall, said wall having an outer exposed mounting surface provided with spaced separate recessed portions,
a terminal conductor strip adapted to be mounted in one of the recessed portions and fixedly positioned on the wall surface,
said wall having an aperture formed therein within said recessed portion,
said strip having opposing faces and having an opening formed therein and through the faces, said strip being superimposed on the wall surface with the opening aligned with the aperture in the wall,
a fastener having a shank portion adapted to be pushed through the aperture and the opening,
locking means carried by the shank portion for self-anchoring engagement with the wall,
an enlarged end on the shank portion to overlie one face of the strip and hold the other face on the wall surface,
electrical connection means carried by the conductor strip,
said wall surface being provided with three elongated recessed portions including outer portions and a center portion, partition walls integrally outstanding from the wall surface perpendicular thereto and arranged in spaced parallel relation separating and defining with the wall surface the recessed portions, a transversely arranged common end wall formed integral with and perpendicular to the wall surface and integral with the partition walls and disposed at one of the ends of the recessed portions, said block being of planar T-shape with the center recessed portion being in axially staggered relation to the outer recessed portions and formed along the leg portion of the block, and said outer recessed portions being formed in the head portion of the block.
